ABSTRACT OF THE DISCLOSURE

A circuit breaker having electrodynamically compensated contacts urged together in their normal closed circuit position. The contacts are locked in closed position but the movable can unlock itself in case of overcurrent. The electrodynamic forces furnish immediately after unlocking an opening force applied to the movable contact.

Current limiting circuit breakers are known. In these apparatus, the path of the current which passes between the closed contacts forms a loop and the electrodynamic forces due to the current in the loop tend to open the movable contacts against the opposing force of the contact pressure biasing springs. In case of short-circuit or of substantial overcurrent, these electrodynamic forces overcome this opposing force and the repulsion of the contacts then makes it possible to obtain a relatively sudden separation of the contacts and the formation of an arc which increases in length to introduce an increasing impedance in the circuit, causing a limiting of the current. This automatic opening of the contacts is reversible until the tripping device of the circuit breaker, which is generally an electromagnetic tripping device but which may also be an electrodynamic tripping device, gives a positive order for the opening of all the poles of the apparatus, unlocking the movable contacts. This control order is given as a function of the instantaneous value of the current when the latter increases above a predetermined value, regardless of the relative position of the contacts which have been separated by the said electrodynamic forces. The repulsion action of the contacts is practically instantaneous but the unlocking which results from the action of the tripping device is delayed by the intervention of inertia, hysteresis phenomena, etc. Precious milliseconds elapse between the start of the automatic electrodynamic opening of the contacts against the contact springs and the actual unlocking of the movable contacts. The automatic opening of the contacts may be hesitant, in particular when the overcurrent is close to the limit value which causes said automatic opening, or when the substantial current decreases in its cycle (or alternation). Weldings and wear of the contacts then occur, making the apparatus unusable sooner or later.

Furthermore an overcurrent of lower value which is incapable of causing the automatic opening of the contacts nevertheless produces a decrease in the contact pressure which also may lead to an excessive heating of the contact studs.

In order to improve this behavior of closed limiting circuit breakers, it has been proposed to introduce into these current-limiting devices with automatic electrodynamic opening an electrodynamic compensation which operates when the device is in its normal closed position. French Pat. 1,316,904 shows such a device in which a dividing of the main contacts makes it possible to divide the current passing through the closed contacts into two parallel branches so as to produce an electrodynamic force

2

which tends to increase the pressure of the closed contacts against the opposing force of repulsion which leads to the automatic opening. In order to make the transition between the compensated condition in closed state of the circuit breaker and the noncompensated condition which causes the automatic opening with limitation of the current, the movable contact executes a swinging movement to open a pair of main contacts to close the arcing contacts and then to open the other pair of main contacts, thus destroying the compensation as a result of the geometric configuration of the conductive parts in question.

In these known devices, the swinging movement of the movable contact is caused by a special electromagnetic or electrodynamic tripping device which intervenes in the mechanical control of the movable contact, resulting in a delayed action which makes the automatic opening problematical. Furthermore, in this known device, the flexible conductor for the feeding of the current to the movable contacts always acts in the sense of destroying the compensation, thus also making the compensation problematical, even in the closed position of the two pairs of main contacts.

An object of the present invention is an improvement in circuit breakers allowing a definite instantaneous automatic transition from the compensated state to the automatic-opening state without the use of special tripping devices and without recourse to subdividing of the main contacts.

Automatic unlocking of a movable contact support member under the action of electrodynamic forces is known from French Pat. 1,273,255, but in a version which does not have electrodynamic compensation and in which furthermore the arcing contacts and the main contacts are all closed in the normal closed circuit position of the device.

Another object of the invention is to provide automatic unlocking of the movable contact members of a circuit breaker having electrodynamic compensated closed contacts. Still another object of the invention is to provide an electrodynamic compensated circuit breaker of a simple and economical design having poles which open automatically and individually towards their normal opening position without intervening of the normal tripping device.

Still another object of the invention is a circuit breaker in which the contacts are electrodynamically compensated until the very moment of their separation, from which moment on the electrodynamic forces cause the rapid opening of the contacts.

Other characteristics and advantages will be clear from the following description of several embodiments of the invention, which are shown in the accompanying drawings in which:

FIG. 1 is a schematic side view illustrating the principle of a known contact device with electrodynamic compensation, the device being shown in its normal closed circuit position;

FIG. 2 shows the same device at the start of its opening stroke under the action of the electrodynamic forces;

FIG. 3 shows the device of FIGS. 1 and 2 after the intervention of the tripping device;

FIG. 4 shows schematically, in side view, a contact device according to the invention in its normal closed circuit position;

FIG. 5 shows this device of the invention as it is just about to unlock;

FIG. 6 shows the device of FIGS. 4 and 5 just after unlocking at the time when the arcing contacts touch each other and then immediately separate in order to establish an arc;

FIG. 7 shows this device at the end of the opening stroke caused by the electrodynamic forces;

FIG. 8 shows this device at the end of the opening stroke after the actuation of the tripping device (not shown);

FIGS. 9, 10, 11, 12 and 13 shows, in side view and partially in section, a practical embodiment of a compensated limiting circuit breaker according to the invention, these figures corresponding to FIGS. 4, 5, 6, 7 and 8 respectively.

FIGS. 14 to 17 show schematically in side view the principle of another embodiment, the different positions corresponding to those of FIGS. 4, 5, 6 and 7 respectively.

In FIGS. 1 to 3 which illustrate a known contact device, a movable contact supporting arm 10 is connected by its end 12 to a connection bar 14 by means of a flexible conductor or strap 16 arranged in the form of a loop. The upper portion of the arm 10 bears a main contact stud 18 and towards the top an arcing contact stud 20, which contact studs cooperate with the main stationary contact stud 22 and the arcing contact stud 24 respectively which are disposed on a stationary contact support member 25 which is connected to the other connecting bar 26. The arm 10 is pivotally mounted by means of a lug 27 on a pin 28 borne by a support member 30 which in its turn is pivoted on a fixed pin 32. The pin 28 is arranged between the end 12 and the upper part of the contact arm 10 and a compression spring 33 which brings the contacts together acts on the end 12, its other end resting against a stationary surface 35. The opening and closing of the contacts is effected by a rotary drive shaft 34, one crank 36 of which is pivoted at 37 on an insulating connecting rod 38, the other end of which is articulated at 39 to an arm 40 which is rigidly connected with the support 30.

In closed position of the main contacts 18, 22 shown in FIG. 1, the support member 30 and the pin 28 are locked by the rod links 36 to 40 and the spring 33 urges the arm 10 in rotation around the pin 28 applying the movable main contact 18 against the stationary main contact 22. The arcing contacts 20, 24 are spaced apart and the assembly is geometrically arranged in such a manner that the electrodynamic forces of repulsion of the contacts 18, 22 are compensated for by the electrodynamic forces produced in the loop 16. This compensation maintains sufficient contact pressure for any value of current.

The opening of the contacts takes place by rotation of the drive shaft 34 in anti-clockwise direction which is caused by a tripping device (not shown) which permits the displacement of the pins 37, 39 and 28 and thereby unlocks the support 30. Under the action of the forces which are applied to it by the arm 10, i.e. the resultant of the electrodynamic forces of repulsion of the contacts and loop and the force of the spring 33, the pin 28 moves, liberating the arm 10 which then pivots around the main contact 22 until the arcing contacts 20, 24 touch (see FIG. 2) and the main contacts are subsequently separated. The compensation effect is destroyed by the spatial position of the arcing contacts and the arm 10 is then suddenly pushed back towards the open circuit position shown in FIG. 3.

In the following figures, the same reference numbers are employed to designate parts similar or identical to those shown in FIG. 1, and these parts will not be described again in detail below.

In FIGS. 4 to 13 which illustrate a first embodiment of the invention, the electrical circuit of the pole is identical to that of FIGS. 1 to 3, as is the mounting of the contact arm 10 by a pin 28 on a support 30 which is articulated at 32. The support 30 has an arm 46 the end of which cooperates with a locking device consisting in the example selected of two rollers 48 and 50 cooperating with a stop 52 which is integral with the arm 46. The roller 48 is borne by the end of said arm 46 and the roller 50 by the end of a lever 54 which is pivoted

at 39 to the end of the operating rod 38. Between the pins 39 and 32 is inserted a knuckle joint comprising two toggle levers 60, 62 pivoted at 58, the opposite ends of which are pivoted at 39 and 32 respectively. An elastic biasing force, produced by compression spring 64 which rests at its ends against a lug 66 of the lever 62 and against the lever 60 respectively, tends to stretch the knuckle joint. The end of a trip rod 70 which is rigidly connected with the locking lever 54 is arranged opposite and a small distance from the element 66 of the lever 62 so that upon a bending of the knuckle joint 58 having levers 60, 62, against the action of the spring 64, it comes against and is acted upon by the element 66, causing the releasing of the locking device 50, 48 by pivoting in anti-clockwise directions of the lever 54 around the pin 39 and therefore the unlocking of the support 30 and the release of the pole. A slot 72 in the lever 54 (see FIG. 9) limits the swinging movement of the locking lever 54 in both directions with respect to the pin 58 which passes through it. A stop 31 which is rigidly connected with the arm 30 limits the pivoting of the arm 10 around the pin 28 and a fixed stop 71 arranged on the stationary side plate 73 receives the roller 28' of the pin 28 at the end of the stroke (see FIGS. 12 and 13).

The contact device of FIGS. 4 to 8 and 9 to 13 respectively operates as follows:

In the "closed and locked" position shown in FIGS. 4 and 9, the support 30 and the arm 46 are urged in rotation around the pin 32 by the electrodynamic forces which are transmitted by the pin 28 in clockwise direction. These forces are also transmitted by the locking device 48, 50 and the lever 54 to the pin 39 whose displacement, by pivoting of the connecting rod 38, is opposed by the knuckle joint 60, 58, 62, 66, 64. The support 30 and the pin 28 are thus locked, the contacts being compensated by the effect of the loop 16, as in the example of FIG. 1. The spring 64 of the knuckle joint 58 is subjected to a compressive force which is proportional to said forces transmitted by the pin 28 to the support 30.

Upon overcurrent or a short-circuit current, the electrodynamic forces acting on the arm 10 increase as well as the reaction on the pin 28 and therefore on the spring 64, which yields, causing a bending of the knuckle joint 62, 60 until the trip rod 70 and the part 66 abut, and from this moment the rod 70 starts to pivot the lever 54 in the anticlockwise direction, in a first stage until the centers of the pins 39, 48 and 50 are aligned. The slight pivoting of the support 30 and the slight translation thus created of the pin 28 towards the right on the figures involves a swinging of the arm 10 in the anti-clockwise direction, decreasing the distance between the arcing contacts 20, 24 without the latter, however, coming into contact, the main contacts serving as a pivot without separating.

If the overcurrent does not exceed a predetermined limit which corresponds to the position of the members in accordance with FIGS. 5 and 10 or if this overcurrent disappears before the tripping proper, the different parts are automatically returned to their initial position, shown in FIGS 4 and 9, under the action of the different elastic forces and in particular of a tension spring 74 which pulls the lever 54 back towards the arm 66. The contact pressure will not have decreased during this entire period.

If the overcurrent increases, the element 66 of the knuckle joint pushes the trip rod 70 and releases the roller 48 from the roller 50 (see FIGS. 6 and 11). The support 30 is then entirely free and swings, the opening of the circuit breaker taking place by the coming into contact with each other of the arcing contacts 20, 24, followed by the separation of the main contacts 18, 22 with rupture of the electrodynamic compensation and by rapid separation of the arcing contacts (see FIGS. 7 and 12). This opening is obtained in powerful manner as a result of the electrodynamic forces of repulsion between the contacts, the compensation being now entirely de-

stroyed, and also as a result of the contact pressure spring 33, since the pin 28 has been freed. The roller 28' of the pin 28 comes against the part 71 and the arm 10 comes against the stop 31.

The locking lever 54 which is stopped by the striking of the left end of the slot 72 against the pin 28 can cause at the end of its stroke the tripping of the conventional automatic opening mechanism (consisting of a tripping device not shown) of all the poles, causing the rotation of the drive shaft 34 in suitable manner. This results in a displacement of the opening rod 38 which returns the lever 54 into reset position by means of the spring 74, ready for another operation (see FIGS. 8 and 13). Upon the closing movement which is controlled by the connecting rod 38, the locking lever 54, arm 46 and knuckle joint 60, 62 constitute practically a rigid assembly which brings the contact arm 10 into closed position. This is also true upon a normal opening operation (manual or by tripping device) during which the parts are brought from the position shown in FIGS. 4 and 9 to the position shown in FIGS. 8 and 13 by displacement of the connecting rod 38 without the opening of the catch 48, 50.

Another embodiment of the invention is illustrated in FIGS. 14 to 17 in which again the pole comprises the support 30 as well as the drive or control shaft 34. The connecting rod 38 of FIGS. 4 to 8 is connected to the pin 39 by an interlock mechanism which comprises a hollow housing 76 rigidly connected with the connecting rod 38 and having a step at 78 leading to a cavity 80. A spring 82 is guided so that it is contained along the extension of a rod 84 which is pivoted at 39. A guide cage 86 of the spring 82 has an inclined plane 88 which cooperates with a stop 90. The compression spring 82 rests against the rod 84, on the one end, and against a lock 92, on the other end. In closed circuit position (see FIG. 14), the lock 92 rests against the step 78. The compression of the spring 82 and the moving together of the parts 38, 84 bring the inclined plane 88 in contact with the stop 90, a continuation of the movement under the action of the electrodynamic forces causing a swinging of the element 82 with respect to the element 76 causing at a given moment the disengagement between the lock 92 and the step 78 and the opening of the pole, the lock 92 coming into the cavity 80.

It is easy to see that the operation of the device of FIGS. 14 to 17 is similar to that of FIGS. 4 to 13. In order to follow the course of the tripping, compare FIGS. 14 to 17 with FIGS. 4 to 8 respectively. The tripping of the other poles which have not been automatically tripped individually (a single pole is shown in the figures) is brought about by the pivoting of the connecting rod 36 in anti-clockwise direction and resets the lock 92 in front of its step 78 after having effected a certain compression of the spring 82 which was relaxed during the tripping due to the lefthand wall of the housing 76 which rests against the lefthand end of the spring 82.

What is claimed is:

1. A circuit breaker comprising an elongated movable contact arm, a movable contact member mounted on a first end portion of said contact arm and cooperating with a relatively stationary contact member, conducting current supply means connected to a second end portion of said contact arm, said conducting means forming part of a current loop, said contact members in their normal closed circuit position being urged together by electrodynamic forces due to currents flowing in said loop, a movable support member for said contact arm, bias means for elastically biasing said support member towards its normal closed circuit position, releasable locking means to confine the movement of said support member between its said normal closed circuit position and a predetermined intermediate position in opening direction, and control means to release said

locking means and adapted to be operated by said support member substantially in its said intermediate position to cause the unlocking of said support member and the opening of said circuit breaker, whereby said electrodynamic forces urge said contact arm towards its open circuit position after unlocking of said support member.

2. A circuit breaker according to claim 1, wherein said contact arm is pivotably mounted on said support member intermediate said end portions.

3. A circuit breaker according to claim 1, wherein said support member is pivotably mounted on a fixed axis.

4. A circuit breaker according to claim 1, wherein said bias means comprise spring means, said control means comprising abutment means abutting upon a predetermined straining of said spring means.

5. A circuit breaker according to claim 4, wherein said control means comprise a toggle lever stressed by said spring means.

6. A circuit breaker according to claim 1, wherein said locking means comprise a roller.

7. A circuit breaker according to claim 4, wherein said abutment means comprise an inclined plane.

8. A circuit breaker according to claim 2, wherein said contact members comprise a pair of main contacts and a pair of arcing contacts, said contact arm executing a swinging movement between upon unlocking of said support member to sequentially close said arcing contacts, open said main contacts and open said arcing contacts.

9. A circuit breaker according to claim 8, wherein said main and arcing contacts are disposed in position so that said electrodynamic forces urge said main contacts together until unlocking of said support member.

10. A circuit breaker according to claim 1, wherein said conducting means comprise a flexible strap.

11. A circuit breaker comprising a pivotably mounted contact arm, a movable main and a movable arcing contact disposed on said contact arm and cooperating respectively with a relatively stationary main and a relatively stationary arcing contact, conducting means to supply current to said movable main and arcing contacts, said movable and relatively stationary main contacts being urged together in their normal closed circuit position by electrodynamic forces due to currents flowing in said conducting means, releasable locking means limiting the pivotal movement of said contact arm between its normal closed circuit position and a position intermediate between said normal closed circuit position and an open circuit position, spring means biasing said contact arm towards said normal closed circuit position, and control means operable by said contact arm to release said locking means and unlock said contact arm in said intermediate position causing the momentary closing of said arcing contacts and the opening of said circuit breaker, the opening movement of said contact arm being accelerated by said electrodynamic forces.

12. A circuit breaker according to claim 11, further comprising independent trip means, the tripping of said trip means causing the resetting of said released locking means before closing of the circuit breaker.
